UNITED STATES PATENT OFFICE.

JOSEPH B. HALL, OF CHICAGO, ILLINOIS, ASSIGNOR TO EDWARD R. WILLIAMS, OF SHARPSBURG, PENNSYLVANIA.

LIQUID-DISPENSER.

1,107,299.

Specification of Letters Patent. Patented Aug. 18, 1914.

Application filed February 25, 1909. Serial No. 480,020.

To all whom it may concern:

Be it known that I, JOSEPH B. HALL, a citizen of the United States, and a resident of Chicago, in the county of Cook and State 5 of Illinois, have invented certain new and useful Improvements in Liquid-Dispensers, of which the following is a specification.

This invention relates to machines for dispensing or delivering liquids in measured 10 amounts, and more particularly to machines for dispensing such liquids as liquid soap, toilet waters, drinking water, beverages, or other liquids.

The object of the invention is to provide 15 simple and effective dispensing apparatus which does away with the necessity for valves or ground fits, springs, pumps or other operating mechanism, and which is arranged at each operation to dispense a 20 definite quantity of liquid of any predetermined amount.

A further object of the invention is to 25 provide liquid dispensing apparatus which is durable and can be easily refilled or replenished.

Further objects of the invention are in 30 part obvious and in part will appear more in detail hereinafter.

In the drawings Figure 1 represents a 35 sectional elevation taken on the line A—A, Fig. 2, and showing one embodiment of the invention; Fig. 2 is a front elevation thereof; Figs. 3, 4, 5 and 6 are detail side elevations, illustrating certain arrangements of 40 the outlet; and Fig. 7 is a sectional elevation of another embodiment of the invention.

Referring to the drawings the reference 45 numeral 1 indicates the receptacle, which may be formed of any suitable material, but preferably is an ordinary glass bottle of any suitable shape. Said receptacle is supported in an inverted position and the liquid is discharged therefrom through a bottom outlet, which may be the neck of the bottle itself, as in Fig. 7, but which in Fig. 1 is shown 50 as a member 7 rigidly secured to the receptacle in a manner to be described.

The entire apparatus is supported by a 55 suitable bracket 14 fastened to the wall in any manner, as by screws 15, 15^a. Said bracket has an outwardly projecting stem surrounded by a sleeve 12 on a hollow member 3, to which the receptacle is secured, as by cement or plaster of Paris 2. Hollow 60 member 3 has a bottom member 4 secured

thereto and is rigidly connected to the outlet member 7, as by conduit 5. The outlet member 7, conduit 5, member 3 and its bottom member 4 may either be parts of the same integral structure or may be separate parts 60 formed of any suitable material, such as metal, and suitably secured to each other, as by soldering. Preferably, the stem on the bracket 14 is provided with an annular groove into which projects the end of a set 65 screw 13 threaded through the sleeve 12, and by means of which the apparatus may be clamped in upright position or may be loosened and inverted for filling.

The discharge of liquid from the device 70 is regulated and controlled by a member which co-operates with the member which forms the outlet from the receptacle, that is, with the neck of the receptacle itself, as in Fig. 7, or; as shown in Fig. 1, with the 75 outlet member 7, which is a continuation of said neck. As shown in Fig. 1, the liquid flow is regulated by a cup 10, which surrounds the outlet member 7 and has an inner 80 chamber or well into which liquid is discharged from the receptacle. The cup is supported by a holding member 9, which may be connected directly to the receptacle itself, but is shown as threaded upon a member 6 suitably secured to or forming 85 part of the outlet member 7. Parts 6 and 7 if separate may be fastened together, and when the holder 9 is screwed up on member 6 it may be locked thereon by suitable means, such as the set screw 8. The cup 10 and holder 9 are of bowl shape, the lower 90 curved wall of the holder 9 forming an annular ledge or shelf upon which the cup is loosely supported, and the cup is of such height that in its bottom position its rim or side wall projects a little above the lower 95 end of the outlet member 7, thereby producing a liquid seal which prevents discharge of the liquid from the receptacle. Holder 9 has a bottom opening through which projects a stem 11 on cup 10. Said stem is slightly 100 smaller than the opening, so that liquid flows therethrough, but it is large enough to guide the cup when it is raised. The cup 10 has an internal diameter slightly greater 105 than the external diameter of the outlet member 7, and has an external diameter slightly less than the internal diameter of the upper portion of holder 9. Liquid is 110 discharged from the receptacle by pressing

upwardly on the stem 11 and thereby lifting the cup. The movement is limited by contact of the cup with the inner surface of member 6. When the cup is lifted a portion 6 of the outlet member 7 enters the chamber or well in the cup and displaces its own volume of liquid therefrom, which liquid passes up between the cup and outlet member 7 and flows down between the cup and holder and through the discharge opening 10 at the bottom of the holder.

In the form shown in Figs. 1 and 2 the conduit 5 is connected to the side of the hollow member 3 and to the top of the outlet member 7, but the arrangement of this conduit, if such a conduit is used, is immaterial. Fig. 3 shows an arrangement where the conduit 5^a is connected to the bottom 4^a of hollow member 3^a and enters the outlet member 7 at one side. Said outlet member has a top 6^a to which the holder 9^a is secured and is provided with an inner depending annular wall 7^a which forms the effective outlet member for coöperation with the cup. The cup 10 surrounds the outlet member 7^a and coöperates therewith to cause the discharge of liquid from the receptacle.

In the form shown in Fig. 4 the conduit 30 5^b is connected to the bottom 4^a of the hollow member 3^a, as in Fig. 3, and opens into the top of the outlet member 7, as in Fig. 1. In Fig. 5 the conduit 5^c is connected to the hollow member 3 in the manner shown in Fig. 1 and its connection to the outlet member is of the same type shown in Fig. 3.

In Fig. 6 the conduit 5^d is connected to the hollow member 3 and the outlet member 7^a in the same manner shown in Fig. 5, the only difference between these two forms being that conduit 5^d is curved or bent so that the outlet member 7^a is at a lower level than member 3, while the conduit 5^d is straight, so that the outlet 7^a and holder member 3 are on about the same level.

In all the forms described the dispensing device may be provided with a sleeve 12 and set screw 13 for rotatably mounting it upon a bracket as above described.

Fig. 7 shows another embodiment of the invention in which the holder for the cup is an integral part with or is rigidly secured to a bracket 32, which may be secured to a suitable support, as by screws 15, 15^e. In the form shown the bracket has a frusto conical upper portion to receive the receptacle 1^b, which is shown as a glass bottle with a conical wall. Bottle 1^b may be secured to the bracket 32, but preferably merely rests loosely thereon. The depending neck of the bottle has a bottom outlet opening and is surrounded by the cup 10^b, which forms a liquid seal at the outlet. Said cup is supported by an annular ledge and 65 may be raised by pressing upwardly on a

stem 11 which projects from an opening in the cup holding member.

17 indicates a valve member having a portion lying within the bottle and arranged when the bottle is filled and inverted to drop down to the constricted mouth and close the bottle. When the bottle is placed in the holder as shown in Fig. 7 the stem of the valve 17 strikes the bottom of the cup 10^b before the bottle seats, so that the liquid will flow from the bottle into the cup. The operation of this form of device is the same as in the prior forms described, the essential difference being that the cup surrounds the neck of the bottle itself, instead of a part secured thereto or a continuation thereof.

To fill the receptacle shown in Figs. 1 to 6 the set screw 13 is loosened and the entire device is inverted on the bracket 14. Holder 9 and cup 10 are then removed and the liquid is poured into the mouth of member 7. The cup and holder are then replaced and the device restored to initial position. In Fig. 7 the bottle is merely lifted out of the holder, filled and replaced.

The entire device is simple, sanitary and inexpensive. It may be used for dispensing any kind of liquid. The details of construction may be varied within wide limits and the invention is susceptible of considerable modification within the scope of the claims hereinafter, without departing from its spirit or sacrificing any of its advantages.

What I claim is:

1. A liquid dispensing apparatus, comprising a receptacle having a neck formed with a discharge orifice, a cup surrounding said neck and having a well into which liquid is discharged from said orifice, a holder for said cup provided with an annular supporting shoulder, and means on said cup engaging said shoulder for normally preventing removal of the cup from the holder.

2. A liquid dispensing apparatus, comprising a receptacle having a neck formed with a discharge orifice, a cup surrounding said neck and having a well into which liquid is discharged from said orifice, a holder for said cup provided with an annular supporting shoulder, means on said cup engaging said shoulder for normally preventing removal of the cup from the holder, and interengaging parts on said holder and cup for guiding the latter during its movement.

3. A liquid dispensing apparatus, comprising a receptacle having a bottom neck formed with a discharge orifice, a holder rigidly secured to said receptacle and depending below the end of said neck, and a cup supported at the lower end of said holder and surrounding said neck and arranged to form a liquid seal therewith, said cup being movable with relation to said

holder and said neck and arranged when moved to cause the discharge of liquid from said receptacle.

4. A liquid dispensing apparatus, comprising a receptacle having a bottom neck formed with a discharge orifice, a holder rigidly and detachably secured to said receptacle and depending below the end of said neck and a cup surrounding said neck 10 and arranged to form a liquid seal therewith and loosely carried by said holder, said cup being movable with reference to said holder and neck and arranged when raised to cause the discharge of liquid from said 15 receptacle.
5. A liquid dispensing apparatus, comprising a receptacle having a bottom neck provided with a discharge orifice, an annular holder secured to said receptacle and depending below the end of said neck and provided with a supporting shoulder, and a cup within said holder and resting loosely on said supporting shoulder, said cup surrounding said neck and arranged to form

a liquid seal therewith and being movable with relation to said holder and neck to cause the discharge of liquid from said receptacle.

6. A liquid dispensing apparatus, comprising a receptacle formed with a neck having a discharge orifice, a cup coöperating with said neck to retain liquid in said receptacle, said cup being movable with reference to said receptacle and arranged when moved to cause liquid to flow over the sides of said cup, and a supporting member for said cup secured to said receptacle, said supporting member being provided with an opening in its lower end and constructed and arranged to receive the liquid flowing over the sides of said cup and convey the same to said opening to be discharged therefrom.
